UNITED STATES PATENT OFFICE

134,300

DESIGN FOR A COMBINED MUSICAL KEY- BOARD AND CASING THEREFOR

John Hubert Hall, Maryville, Tenn.

Application August 13, 1942, Serial No. 107,919

Term of patent 14 years

To all whom it may concern:

Be it known that I, John Hubert Hall, a citizen of the United States residing at Maryville, in the county of Blount and State of Tennessee, have invented a new, original, and ornamental Design for a Combined Musical Keyboard and Casing Therefor, of which the following is a specification, reference being had to the accompanying drawing, forming part thereof.

Fig. 1 is a top plan view of the keyboard portion of the combined musical keyboard and casing therefor, showing my new design.

Fig. 2 is a front elevational view of the keyboard portion as it appears when assembled on its roller elements.

Fig. 3 is a front elevational view of the casing in which the rollers and keyboard are housed; and

Fig. 4 is an end elevational view thereof.

I claim:

The ornamental design for a combined musical keyboard and casing therefor, as shown and described.

JOHN HUBERT HALL.
